REFRIGERATING APPARATUS

John Kirgan, Easton, Pa., assignor to Ingersoll-Rand Company, Jersey City, N. J., a corporation of New Jersey

Original application May 8, 1936, Serial No. 78,528.
Divided and this application August 13, 1937,
Serial No. 158,831

6 Claims. (Cl. 62—126)

My invention relates to refrigerating apparatus, and especially to refrigerating apparatus comprising a vessel in which a liquid refrigerant is cooled by vaporizing part thereof and 5 evacuator means of the thermo-compressor type to remove from said vessel the vapor so formed and transfer it to a suitable condenser.

This application is a division of copending application of John Kirgan, Serial No. 78,528, filed May 8, 1936, now matured into Patent No. 2,123,735, dated July 12, 1938.

An object of the invention is to provide refrigerating apparatus of this kind that is compact in design to enable space to be saved both 15 horizontally and vertically wherever it is installed. It is also an object to provide refrigerating apparatus having an evaporator vessel and a condenser disposed one above the other, with the evacuator means so connecting said 20 parts as to reduce the size of the whole to a minimum. In the preferred construction the condenser is at the top, and the evacuator means couples the condenser to the upper part of the evaporator where the vapor is created, and, without adding to the total height, still has the 25 requisite length for efficient operation.

Another object is to provide refrigerating apparatus having evacuator means arranged to carry off vapor from the evaporator through a 30 discharge flue that passes through the evaporator, but is insulated therefrom, to prevent transference of heat thereto.

An additional object is to provide in a refrigerating apparatus built as set forth above 35 with a central flue to deliver the vapor to the condenser, an evaporator containing multiple chambers and simple means for controlling the inflow and outflow of the refrigerant to permit easy and quick adjustment for full load or part load output.

A further object of the invention is to provide refrigerating apparatus which is easily assembled and the various parts whereof are so disposed that the entire unit is strong and rigid 45 and braced by the various members constituting same.

With these and other objects and advantages the invention consists in the arrangement illustrated in the drawing and pointed out in the 50 appended claims; and though only a single form of the improvement is disclosed, I may of course make various changes in the embodiment set forth without departing from the principle of the invention, or exceeding its scope and spirit.

In the drawing, Figure 1 is a vertical sectional

view through the refrigerating apparatus according to this invention, and

Figure 2 is a horizontal section on the line 2—2 of Figure 1.

In the form shown in the drawing the numeral 5 1 indicates an evaporator vessel or tank to which the liquid refrigerant, such as water, to be cooled is admitted at the side near the lower end through an inlet port 2. In this vessel some of the refrigerant is vaporized and the vapor is withdrawn 10 through one or more outlet ports 3 in the sides at the top by means of steam ejectors or evacuators 4. These ejectors create and maintain a vacuum of the desired degree in the evaporator 1 so that the formation of vapor is accomplished. The vapor withdrawn from the evaporator is transmitted to a condenser 5, which is preferably above the evaporator, and liquefied, while the main body of the liquid which is cooled is drawn out through the bottom of the evaporator 1 by way of a conduit 6. The refrigerant entering the evaporator by way of the inlet 2 is at such temperature that part of it will be vaporized at once, the vacuum in the evacuator being maintained high enough for this purpose. 20

To enable the system to operate efficiently at less than full load the evaporator is divided by spaced vertical partitions 7 into a plurality of 30 separate chambers 8. The lower extremities of these chambers 8 are determined by the false bottoms 9 located at the same level near the lower end of the evaporator, and the evaporator has a central sleeve 10 extending through it from top to bottom. A discharge pipe or flue 11 for 35 the evacuators 4, passes up through this sleeve into the condenser 5. These evacuators are at no point higher than the top of the evaporator, and they extend away from the condenser to provide sufficient length of discharge conduit 40 26 without increasing the overall height of the structure. The evacuators are connected to the flue 11 below the evaporator. This flue is somewhat smaller in diameter than the bore of the sleeve so that a space 12 lies between the two and 45 this space may be an air space or be filled with insulation so that there is a minimum transfer of heat between the parts 10 and 11.

Within the chambers 8 are vertical partitions 14 similar to the partitions 7 which are spaced 50 around and extend from the sleeve 10 to the side wall of the evaporator 1. In the construction shown the partitions 7 extend from the bottom 9 to the top of the evaporator 1, whereas the partitions 14 extend from the bottom 9 but 55

terminate short of the top of the evaporator tank. Hence, since for each partition 7 there is a corresponding partition 14, a pair of wells 13 are formed which are bounded by the partitions 7 and 14, the wall of the evaporator vessel 1, and the sleeve 10. The wells 13 are open at the bottom since each section of the false bottom 9 has the same general shape as the cross section of one of the chambers 8 and is secured to a partition 7 on one side and to a partition 14 on the opposite side. Just below the false bottoms 9 is a transverse compartment 15 which is normally full of water or other liquid refrigerant coming in through the inlet 2, this compartment being formed by the false bottoms 9 and a second false bottom 16 that is above the lower end of the evaporator and forms a compartment 17 which is drained by the outlet conduit 6. The wells 13 are in open communication through the open bottom thereof with chamber 15. Thus the wells 13 are supplied with liquid refrigerant from the chamber 15 which rises in the wells and flows over the tops of the partitions 14 to the chambers 8 where the refrigerant is cooled. The second bottom 16 is in the form of an annular ring and completely encircles the sleeve 10. Both bottoms are pierced by the tubular members 19 through which the chilled liquid is conveyed from the chambers 8 to the lower compartment 17. Of course if desired the partitions 14 may have openings 34 therein below the top edges thereof to divide the water entering the chambers 8 into a number of sprays or jets.

In operation when the evaporator receives a liquid refrigerant, such as water, through the inlet 2 the water will rise from the compartment 15 through the wells 13 and will flow over the upper edges of the shorter partitions 14 and downward into the chambers 8. Owing to the vacuum produced in the chambers 8 by the evacuators 4, part of the water is vaporized and the vapor is drawn out through the outlets 3 while the remainder of the water remains liquid and is cooled, flowing out through the passages 19 into the compartment 17, and is drawn off through the pipe 6. The pump 20 causes the cooled water to circulate and forces it into a cooling coil 21 located at a place where a refrigerating effect is desired. The refrigerant in this cooling coil absorbs heat and after being warmed is returned through a connection from one end of this cooling coil to the inlet 2 and cooled over. Each of the ejectors 4 comprises a steam chest 22 which receives steam through a pipe 23. At 24 are the steam nozzles which direct a jet of fluid into the mouths 25 of tubular casings 26 connected to the ejectors 4, these casings being L-shaped and communicating with the central flue 11 at their lower ends. By way of example, I show only two evacuators and two chambers, and use in this case a four-way fitting indicated at 27 beneath the evaporator 1, this fitting resting upon a tubular pedestal 28. One way through the fitting is connected to the conduit 11 and two more are joined to the lower end of each of the casings 26. The fourth way is sealed by a closure 29 so that steam and vapor in the casings 26 must pass upward through the conduit 11 into the condenser 5.

The ejectors 4 are secured to the sides of the evaporator by suitable flanges and other fastening means and the lower end of the conduit 11 may be flanged so as to enable the evaporator to rest thereon. The fitting 27 and the pedestal 28

are likewise flanged to enable the pipe 11, the casings 26 and this pedestal to be easily connected together. Of course more chambers and evacuators may be employed, and the fitting 27 will then have more than four ways through it. If necessary the member 27 may of course be provided with proper draining facilities (not shown) for the removal of any liquid which may collect therein or flow down the flue 11.

The condenser 5, preferably of the barometric type, has an opening 30 in its top to be connected to an evacuator for withdrawing air and non-condensable gases from the condenser and a cooling liquid is supplied to the interior of the condenser through a pipe 31. Within the condenser are deflector plates 32 which are staggered so that the water coming in through the pipe 31 is divided and the vapors entering the condenser from the conduit 11 are caused to mingle with the water and give the greatest liquefying effect. The water and liquefied steam are drained out from the condenser by pipe 33.

With this construction it will be seen that the apparatus is very compact and strong and the parts are disposed so that effective operation under varying working conditions is facilitated. If it be desired to run at part load, the steam for one of the ejectors 4 can be cut off by shutting a suitable valve (not shown) in the pipe 23. In the chamber 8 which is connected to a non-operating ejector the pressure will rise until it equals the pressure in the condenser, and the level of the refrigerant in the associated well 13 will then automatically sink so that it will no longer flow over the top of the partition therein. Also the pressure in that chamber will force down the level of the water in the passage through the member 19 thereof. The non-operating chamber, shown at the left in Figure 1, is thus sealed by the refrigerant in the compartment 17 and in its well 13, while the other chamber or chambers continue to refrigerate. Hence no valves except the valves for the steam pipes 23 are needed. At the same time the construction is very simple and can be assembled and set up or taken down merely by removing the bolts or other fastenings (not shown) which hold the evaporator 1, evacuators 4, casings 26 and the parts 27 and 28 together.

It will be seen that the warm refrigerant returning from the coil 21 to the wells 13, which it reaches by passing through the compartment 15, makes contact with the false bottoms 9 and 16 which are also in contact with the chilled water. Some heat is of course transferred through these bottom plates from the warmed returned water to the outflowing chilled water, but this transfer does not constitute a loss of refrigeration because any heat given to the chilled water by the return water reduced the quantity of heat which must be removed from the return water in the evaporator 1. Such heat as may be taken up by the chilled water is not enough to materially raise its temperature. To prevent other heat losses the barometric condenser 5 on top of the evaporator 1 may be so mounted on the evaporator 1 that an air space (not shown) can be enclosed between the top of the evaporator and the bottom of the condenser; or the condenser may be separate and any suitable heat insulating material may be placed between the bottom thereof and the evaporator. In practice the top of the evaporator will always be filled with vapor caused by vaporization of the refrigerant, and even if the influence of the condenser heats this vapor slightly, it will

not have any noticeable effect on the normal operation of the evaporator or to reduce the capacity of the steam jet boosters.

I claim:

5. 1. Refrigerating apparatus comprising an evaporator tank having a pair of spaced transverse partitions therein forming an inlet compartment therebetween, an inlet for liquid to said compartment, a plurality of spaced vertical partitions in the tank extending upwardly from the higher of said transverse partitions, said vertical partitions being grouped in pairs to form alternate liquid wells and vaporization chambers therebetween, said chambers being rendered non-15 communicating by every second vertical partition and each of said wells being in free communication with the inlet compartment and one of said chambers, outlet means for vapor from the chambers, and means forming a discharge 20 passage for liquid from each of said chambers, said means extending through both of said transverse partitions.

2. Refrigerating apparatus comprising an evaporator having a chamber and an inlet compartment therein leading to the chamber and an outlet compartment below the inlet compartment, and means forming passages leading from the chamber passing through the inlet compartment to communicate with the outlet compartment.

30 3. Refrigerating apparatus comprising an evaporator tank having spaced vertical partitions therein, said partitions dividing the tank into separate chambers and spaces therebetween which form wells for admitting liquid to said chambers, the tank also having outlets for vapor from the chambers.

4. Refrigerating apparatus comprising an evaporator tank having spaced vertical partitions therein, said partitions dividing the tank into separate chambers and spaces therebetween which form wells for admitting refrigerant to 5 said chambers, and alternate partitions terminating below the top of the tank to permit each of the wells to communicate with a chamber.

5. Refrigerating apparatus comprising an evaporator tank having a tubular sleeve extending vertically therethrough, vertical partitions cooperating with the sleeve and spaced therearound, certain of the partitions dividing the interior of the tank into separate vaporization chambers and the other partition cooperating 10 with said certain partition to form inlet wells for admitting refrigerant into said chambers, and outlets in the tank for vapor from the chambers.

15 6. Refrigerating apparatus comprising an evaporator tank having a tubular sleeve extending vertically therethrough, adapted to receive and install a discharge flue enclosed by the sleeve, and a plurality of vertical partitions in the tank spaced around said sleeve to divide the interior of the evaporator into a plurality of separate 20 chambers, said partitions being grouped in pairs, each pair forming a space therebetween, and said sleeve co-operating with said partitions to divide said spaces into inlet wells for admitting refrigerant to the chambers, one partition of 25 each of said pairs extending the full height of the chamber to seal one chamber from the next and the other partitions terminating below the top of the chambers to permit refrigerant to 30 flow from said wells into said chambers. 35

JOHN KIRGAN.
